[57] CLAIM

The ornamental design for a beverage dispenser, substantially as shown and described.

DESCRIPTION

FIG. 1 is a perspective view looking downward at the front, top and right side of a beverage dispenser, showing our new design;

FIG. 2 is a front elevational view thereof;

FIG. 3 is a right side elevational view thereof, the left side being the mirror image of the right side;

FIG. 4 is a top plan view thereof; and

FIG. 5 is a back side elevational view thereof.
